COOKIE JAR

Walter D. Starnes, Los Angeles, Calif., assignor to Walter Starnes, Inc., Los Angeles, Calif., a corporation of California

Application January 9, 1956, Serial No. 39,674

Term of patent 3½ years

(Cl. D58—25)

Fig. 1 is a perspective view of a cookie jar showing my new design.

Fig. 2 is a side elevational view as seen from the opposite side of Fig. 1.

The shading to show contour as applied to the jar in Fig. 1 has been omitted in Fig. 2 for convenience of illustration.

I claim:

The ornamental design for a cookie jar, substantially as shown and described.
